UNITED STATES PATENT OFFICE.

EMERSON B. CAMPBELL, OF BAKERSFIELD, CALIFORNIA.

SUCKER-ROD JOINT.

SPECIFICATION forming part of Letters Patent No. 735,030, dated July 28, 1903.

Application filed February 24, 1903. Serial No. 144,765. (No model.)

To all whom it may concern:

Be it known that I, EMERSON B. CAMPBELL, a citizen of the United States, residing at Bakersfield, in the county of Kern and State 5 of California, have invented certain new and useful Improvements in Sucker-Rod Joints, of which the following is a specification.

My invention relates to improvements in sucker-rod joints for deep wells, the object 10 of my invention being to provide a joint which shall be more economical in use than those heretofore used.

My invention therefore resides in the novel construction, combination, and arrangement 15 of parts for the above ends hereinafter fully specified, and particularly pointed out in the claim.

In the accompanying drawings, Figure 1 is a perspective view showing a sucker-rod 20 joint of my improved construction. Fig. 2 is a longitudinal section of the same in the position the parts occupy while the rod-sections are being united. Fig. 3 is a similar view showing the device in the casing, parts 25 being broken away.

The joint heretofore chiefly in use in pumping deep wells, such as oil-wells, is that known as the "Acme" joint, in which the lower end of the upper rod is formed with a socket threaded 30 on its inner surface, into which is screwed the threaded lug or boss, extending upward from the upper end of the lower rod. It has also been necessary to provide on the upper end of the lower rod around said boss a shoulder against which the lower edge of the cup 35 abuts to form a friction-joint. This was necessary to prevent the rods unscrewing from each other, since the upper rod was held stationary while the lower rod, connected to the 40 plunger, could rotate. The objection to this form of joint was that if the joint became broken, worn out, or useless in any way the whole rod was rendered useless, since the cup and shoulder were of much greater diameter 45 than the rod.

It is the object of my invention to provide a joint which will permit of the rods being used over again when the joint wears out or becomes useless and at the same time will 50 prevent unscrewing of the rods equally as well as with the old form of joint.

Referring to the drawings, 1 represents the

rod-sections, and 2 is a coupling therefor, which is tapped entirely through. Into the ends of the coupling 2 are screwed the ends 55 of the rod 1, thus uniting the rods together. In the side of the coupling is an aperture 3, leading from the interior to the exterior. The contour of surface of the coupling around the outer end of said aperture is free from protuberances. The success of the device is due to 60 this aperture. Without it it has been found that a quantity of oil and sand is inclosed within the coupling between the two ends of the rods. A cushion is thus formed between the 65 two ends of the rods. Now it has been found by practice that the above threads cannot be relied upon to afford sufficient friction to prevent the rods from unscrewing. It is absolutely necessary to have abutments which by frictional contact with each other prevent unscrewing of the rod. By providing the aperture 70 3 the oil and sand are allowed to escape, and the rods may be allowed to be screwed up tight one against the other. They then receive 75 the jar of the oscillation one from the other, and it is not received by the coupling, and thus the friction is sufficient to prevent unscrewing. The utility of this construction will appear 80 from the considerations. It is frequently necessary to repair the pumps of oil-wells, and when this is done the rods have to be pulled out and disconnected and laid down, and as soon as the part of the pump attached 85 to the lower end of these rods has been repaired they are immediately replaced. California oil being of a high specific gravity does not leave the rods freely and readily; but when the rods are being taken out and disconnected the oil is slowly dripping down 90 and is still doing so when they are being replaced. This oil falls directly into the open end of the coupling, as the coupling is always directly under a rod when it is being connected or disconnected. This oil being of an 95 asphaltic base is sticky and cannot be freely removed except by gasoline, so that it would require too much time to attempt to clean out this socket or coupling. The utility of the aperture is now apparent. As soon as 100 the rod is screwed down into the coupling the oil is forced out through the aperture, which allows the rods to be screwed tight together. This they could not do if this cushion of oil.

remained in the coupling. The aperture is therefore of very great importance.

4 represents jam-nuts which are screwed down in the ends of the rods onto the ends of 5 the coupling and which prevent the unscrewing of said rods from said coupling.

I claim—

In combination with sucker-rod sections, a hollow coupling therefor having a small lateral perforation for draining the oil and sand 10 from the interior of the coupling between the

ends of the rod-sections, the contour or surface of the coupling around the outer end of said perforation being free from protuberances, substantially as described.

In witness whereof I have hereunto set my hand in the presence of two subscribing witnesses.

EMERSON B. CAMPBELL.
